UNITED STATES PATENT OFFICE.

RAY STEWART FOX, OF BLUE EARTH, MINNESOTA.

STAKE-PULLER.

1,221,718.

Specification of Letters Patent.

Patented Apr. 3, 1917.

Application filed November 17, 1916. Serial No. 131,846.

To all whom it may concern:

Be it known that I, RAY STEWART Fox, a citizen of the United States, and a resident of Blue Earth, in the county of Faribault and State of Minnesota, have invented 5 an Improvement in Stake-Pullers, of which the following is a specification.

My invention is an improvement in stake pullers, and has for its object to provide a 10 device of the character specified, especially adapted for pulling posts, stakes and the like from the ground, wherein the pulling mechanism is in the form of pivotally connected open frames adapted to be slipped 15 over the post, each frame having at one end gripping mechanism for engaging the post or stake, and at the other end a handle.

In the drawings:

Figure 1 is a perspective view showing 20 the improvement in use.

Fig. 2 is a side view with the puller in section.

Fig. 3 is a front view of the puller in closed position.

25 As is known, in pulling posts or stakes, a large amount of the strength of the one who pulls is wasted in gripping the post or stake. Furthermore, should the stake happen to be broken off near the surface of the 30 ground, there is not sufficient length of post or stake to permit a grip to be obtained.

In the present embodiment of the invention, a pair of open substantially rectangular frames is provided, an inner frame 1 and 35 an outer frame 2, the inner frame being of such size that it will fit within the outer frame. The adjacent side members of the frames are pivoted together near one end of the frame, as indicated at 3, the pivotal connections being in alinement and the end members of the said frames nearest the pivotal connection have teeth 4. These teeth 40 of the frames extend in opposite directions,

that is the two series of teeth face each other, and the opposite end members of the 45 frame are formed into grips or handles 5. In the present instance, the handles are formed by rounding the inner surface of the end members.

In use, the device is arranged as shown 50 in Figs. 1 and 2, the handles being moved away from each other in a direction such that when the opposite ends of the frames separate the teeth will be at the inner sides of the end members and in position to engage the post or stake. The frames are now dropped down over the post in the manner shown, and it will be evident that all of the strength of the one pulling may be exerted in a direct upward pull. Grasping the handles at each side of the post, a direct upward pull is given, and it will be evident that the greater the force exerted the more tightly the device will grip the post, since the force exerted in upward pull acts to 65 sink the teeth deeper into the post. If the post happens to be broken off close to the ground, a secure grip may be yet obtained.

I claim:

A device of the character specified comprising a pair of open substantially rectangular frames fitting one within the other, the side members of the frame being pivotally connected to permit the frame to move into register with each other or with their 70 planes at an angle to each other, the said members having teeth at one end and facing in the opposite direction, and having the end members at the other end concavo-convex, and arranged with the convex surface 75 inward to form handles, said teeth being adapted to grip an object where upward traction is exerted on the handles, the pivotal connection between the frame being near the end having the teeth.

RAY STEWART FOX.
